UNITED STATES PATENT OFFICE.

WILLIAM M. DOERING AND CHARLES J. DOERING, OF CINCINNATI, OHIO.

CARTON-DISPLAY RACK.

Application filed July 9, 1920. Serial No. 394,884.

To all whom it may concern:

Be it known that we, WILLIAM M. DOERING and CHARLES J. DOERING, citizens of the United States, and residing at Cincinnati, 5 in the county of Hamilton and State of Ohio, have invented a new and useful Improvement in Carton-Display Racks, of which the following specification is a full disclosure.

This invention relates to a carton holding 10 magazine or display rack whereby a quantity of cartons can be compactly held and combined for packing purposes, and sustained in a row in an upright position for exhibition purposes, to advertise a supply of merchandise in its retail packages or cartons and provide a holder from which the carton can be taken as the displayed merchandise is sold.

An object of the invention is to provide a 15 panel for compactly combining a quantity of cartons in a row side by side, the panels having projecting series of tabs at each of the opposite ends, each tab foldable to engage into an end of the carton, the tabs at one end being of graduated or relatively different dimensions for convenient consecutive individual tucking in of the tabs into the ends of the cartons, thereby facilitating the tab insertion and preventing the accidental withdrawal of one while a second is inserted.

Another object is to provide a carton holding 20 magazine for compactly holding a quantity of cartons side by side and individually removable therefrom, and possessing the characteristics of an easel adapting the cartons to be unitarily supported for exhibition purposes.

Another object of the invention is to provide a carton having a panel rack or easel for holding a quantity of containers or cartons and detachably engaging with the opposite ends of containers or cartons and a foldable back stay secured and swivelled upon the rear side of the panel adapted in a knock-down position to lie flat and parallel therewith, and capable for its set up position to be swung to project an end of the back stay above the containers or cartons to provide for an advertising space.

Additional objects and certain advantages 45 will be set forth in the description, and reference is made to the drawings forming a part of this specification in which,

Fig. 1 is a front elevation showing our display-rack set as in use.

Fig. 2 is a central vertical transverse section.

Fig. 3 is a fragmentary plan, showing the vertical relation of the upper and lower flaps.

Fig. 4 is an edge elevation illustrating the initial operation of placing the cartons upon the rack.

Fig. 5 is a view similar to Fig. 4, showing the carton in position, and illustrating the manner of inserting the lower flap.

Fig. 6 is a fragmentary front elevation of Fig. 5.

Fig. 7 is a plan view of the blank.

Fig. 8 is a plan view of the reverse side of the rack in its flat knock-down form.

In carrying out our invention, we provide 70 a blank, (see Figs. 7 and 8) of sheet cardboard of substantially rectangular configuration, upon the top edge of which is formed a series of tabs 2, of equal size and equally spaced apart. Upon the lower or opposite 75 edge is formed a series of tabs 3 equal in number and width to the tabs 2 and in vertical alignment with said tabs, but of graduated length relatively for a purpose herein-after explained.

The tabs 2 are subsequently folded along the line 4. The blank is divided by a scored line providing a body or panel portion 5 and a horizontal shelf or back portion 7 bent at right angles to the body or panel along the 85 scored line 4 and the tabs 3 are then bent to a substantially vertical position, or at an angle to the shelf or base portion.

Upon the rear side of the body portion 90 a foldable back stay is secured by an eyelet or rivet 8 at a point preferably centrally of the body portion, the connection of the parts being such as to permit the back stay to be swivelled upon the panel for adjusting the parts to a compact knock-down position.

The back stay or supporting member is 95 formed of sheet cardboard and in its flat condition approximately of width dimension as a height dimension of the panel and is designed to be swung to a position shown in Fig. 8, when the display-rack is in knock-down position.

At approximately two-thirds of its height from its bottom edge and at approximately

one-third of its width from each side, the blank is cut as at 15, 16, to form portions 17, 18, to be folded along the lines 19, 20, at right angles to the intermediate portion to 5 serve as supporting wings or braces, the bottom edges 21 of which are designed to rest upon the surface on which the magazine display-rack is set. At a short distance from its bottom and formed symmetrically on each 10 side of the vertical center of the supporting member blank is an opening 25 of the configuration shown.

A locking flap 26 of the configuration shown is formed by folding along the line 15 27, and notches 28 are provided, which notches engage the vertical edges 29 of the opening 25 when the portions 17, 18, are folded at right angles to the body portion 6 to form supporting wings or back stays for 20 the structure as an easel, the under surface of the locking flap 26 engaging and resting upon the slightly inclined edges 30, all for the purpose of locking the supporting wings in operative position.

25 A portion 9^a of the supporting member or back stay 9 projects above the upper line of the tabs and its front face provides an advertising space above the carton held by the magazine.

30 The upper and lower tabs each are of a size so that each is respectively adapted to be engaged or tucked into an end of the carton 31, and are spaced apart relatively to hold a quantity of cartons side by side.

35 The tabs, upper and lower, are arranged in aligned pairs for engagement into the opposite ends of the cartons. The magazine is constructed to receive and hold a carton of commercial type of construction in which 40 its folding end flaps of each carton respectively tuck in at relative opposite sides of the cartons. Commonly the upper end closing flap tucks in at the rear side of the carton and the base closing flap at the front 45 side of the carton. It is therefore that the top tabs tuck into the upper end of the carton between the rear side of the carton and the tucking end of the upper closing flap, while the lower tabs, projecting from

50 the base wall or leaf of the panel, are extended forwardly by said base wall, to align and be engaged or tucked into the lower end of the carton, at the forward side thereof, between the front wall of the 55 carton and the tucking end of the lower closing flap. If the head and base of the carton is reversed the panel and back stay can be reversed, the construction of easel being susceptible to such use, the advertising space in such instance will assume its 60 normal position, while the panel is reverse.

It is also contemplated that the invention

is capable for use with cartons in which the down flaps tuck in at relatively the same side of the carton.

For inserting the carton upon the magazine the following operations are performed:

The flaps 2 (see Fig. 4) are bent at right angles to the body portion 6 and the carton flaps 32 are slightly separated from their sides 33, and the flaps 2 are introduced therebetween as shown.

The cartons are then pushed toward the body 5, and swung downwardly in the direction of the arrow to bring their bottoms 75 to a position shown in Fig. 5. The shelf portion 7 is then bent upwardly, as shown, and the flaps 3 are bent to substantially right angled position, and the right hand flap 3^a, (see Figs. 5 and 6) first inserted between the carton flap 35 and the side 36 thereof, after which the remaining disengaged flaps 3 are consecutively inserted into their respective cartons, and the shelf 7 is raised to abut the under surfaces of the cartons, as shown in Fig. 2.

The tabs 3 are relatively graduated or of different lengths in successive order, the end tab 3^a being slightly longer than its next adjacent tab and so on which facilitates the 90 insertion of the tabs into the ends of the cartons consecutively until all have been partially inserted into the carton, whence they can be punched as a unit.

Having described our invention, we claim:

1. In an article of the class described, a base of semi-flexible sheet material, having a series of tabs formed along each of two opposite edges in aligned pairs, the tabs of one series being of graduated length relatively, said tabs in pairs arranged to be tucked respectively into opposite ends of a carton for removably securing the carton upon the base.

2. In an article of the class described, a base having rows of tabs formed along each of the two opposite parallel edges, each tab of each row being of equal width, equally and slightly spaced apart, the tabs of one row adapted for insertion between the end flap and side of one extremity of each of a series of cartons, the tabs of the other row being of graduated length, adapted for successive insertion between the end flap and side of the opposite extremity of each carton of the said series.

In witness whereof, we hereunto subscribe our names, as attested by the two subscribing witnesses.

WM. M. DOERING,
CHARLES J. DOERING
